UNITED STATES PATENT OFFICE.

JOSEPH M. BROKAW, OF BATTLECREEK, MICHIGAN.

CORN-CRIB.

SPECIFICATION forming part of Letters Patent No. 703,529, dated July 1, 1902.

Application filed August 10, 1901. Serial No. 71,569. (No model.)

To all whom it may concern:

Be it known that I, JOSEPH M. BROKAW, a citizen of the United States, residing at Battlecreek, in the county of Calhoun and State 5 of Michigan, have invented a new and useful Corn-Crib, of which the following is a specification.

This invention is an improved corn-crib, the object being to provide a crib in which the 10 contents will be thoroughly ventilated; and a still further object is to provide a corn-crib in which the contents will be fully protected against lateral storms or rain, sleet, or snow.

With these objects in view the invention 15 consists, essentially, in constructing the crib with double side walls, the inner walls being perforated, the bottom being preferably perforated and the roof provided with ventilators.

The invention consists also in certain de- 20 tails of construction and novelties of combination, all of which will be fully described hereinafter, and pointed out in the claim.

In the drawings forming part of this speci- 25 fication, Figure 1 is a perspective view of a corn-crib constructed in accordance with my invention, the outer sheathing being broken away to disclose the inner wall. Fig. 2 is a transverse vertical section. Fig. 3 is a horizontal section, and Fig. 4 is a detail view 30 showing a portion of wire-cloth that may be used instead of the perforated sheet-iron.

In carrying out my invention I employ a framework comprising the lower timbers A, the upper timbers B, and the studding-timbers 35 C. A suitable roof E is arranged upon the upper timbers B, said roof being provided with ventilators F. The outer sheathing G, which is secured to the outer face of the tim-

bers, may be of wood or metal, and the door G' may be arranged at one or both ends of the 40 crib.

H indicates the perforated bottom, prefer- 45 ably constructed of metal, and I indicates the perforated side walls secured upon the inner face of the studs, as most clearly shown in Figs. 2 and 3.

By having the bottom H and the inner walls I formed of perforated metal the contents of the crib are thoroughly ventilated and at the same time are protected against the inroads 50 of animals. By having the crib constructed with double walls the contents of the crib is not subjected to wetting by lateral wind, rain, or snow storms.

It will thus be seen that I provide a crib in 55 which corn or other grain can be safely stored for an indefinite time.

I may find it desirable in some cases to con- 60 struct the inner walls with wire-cloth, and in that case I would use the cloth similar to that illustrated in Fig. 4 of the drawings.

Having thus fully described my invention, what I claim as new, and desire to secure by Letters Patent, is—

A corn-crib comprising the upper and lower 65 frames, and the side studding-timbers, and the legs supporting the lower frame above the ground, the perforated metallic bottom and inner side walls, the imperforate outer side walls, the imperforate roof provided with ven- 70 tilators, and a door by which access is had to the crib substantially as shown and described.

JOSEPH M. BROKAW.
